(57) **CLAIM**

I claim the ornamental design for a footwear upper portion, as shown and described.

DESCRIPTION

FIG. 1 is an upper left side perspective view of an upper portion of an article of footwear; and,

FIG. 2 is a left side elevational view thereof.

The ornamental design that is claimed is shown in solid lines in the drawings. The broken lines shown in FIGS. 1 through 2 are included for the purpose of illustrating environmental elements only and form no part of the claimed design.
